UNITED STATES PATENT OFFICE.

WILLIAM WOLFE AND DENNIS PARKS, OF ST. LOUIS, MISSOURI.

MACHINE FOR CUTTING PIECED LIFTS AND FOR BUILDING HEEL-BLANKS THEREFROM.

1,268,908.

Specification of Letters Patent. Patented June 11, 1918.

Application filed December 31, 1914. Serial No. 879,858.

To all whom it may concern:

Be it known that we, WILLIAM WOLFE and DENNIS PARKS, citizens of the United States, residing in the city of St. Louis and State of Missouri, have invented new and useful Improvements in Machines for Cutting Pieced Lifts and for Building Heel-Blanks Therefrom, of which the following is a specification.

- 10 This invention relates to the art of heel building, and has for its general object to provide a novel machine for cutting pieced lifts and for building heel-blanks therefrom in a continuous operation.
- 15 Detailed objects of the invention are, to provide novel means for cutting straight edges on pieces of scrap leather to enable such pieces to be assembled to form the pieced lift; to provide novel means for cutting assembled pieces of leather into the form of a lift and simultaneously forcing the pieced lift thus formed into a holder; to provide a combined die and heel-blank holder of indefinite length in combination 20 with a cutting-block coöperating therewith; to provide, in combination with constantly-acting cutting means, a member movable thereby to actuate the cutting block; to provide novel means for enabling a rand to be applied to the heel-blank; to provide novel 25 means for indicating the thickness of each lift cut and forced into the holder and thereby to determine when each heel-blank has been built up to the proper height. Other 30 objects of the invention relate to details of construction and to combinations and operations of parts as will hereinafter more clearly appear.

In the drawings—

- 40 Figure 1 is a view in rear elevation of the machine, with the parts in the normal position;

Fig. 2 is a view in front elevation showing the cutting block moved to a position over the die and momentarily depressed by the actuating member;

Fig. 3 is a plan view with the parts in normal position;

Fig. 4 is a similar but fragmentary view 50 with the cutting block moved to a position over the die;

Fig. 5 is a broken sectional view taken on the line 5—5 of Fig. 1, and viewed in the direction of the arrows;

55 Fig. 6 is a plan view of the assembling table surrounding the die and showing

pieces of leather assembled thereon in readiness to be cut by the descent of the cutting block thereon, the rand adjuster employed being shown turned to an inoperative position;

Fig. 7 is a similar view, a pieced lift having been cut from the piece of leather shown in Fig. 6 and forced into the die, the rand adjuster having been turned to operative 65 position over the die, and a rand placed in position therein over the die in readiness to be cut by the depression of the cutting block;

Fig. 8 is a fragmentary central vertical 70 sectional view taken on the line 8—8 of Fig. 7;

Fig. 9 is a sectional plan view on the line 9—9 of Fig. 8, but showing the upper lift of a heel-blank supported in the holder; 75

Fig. 10 is a plan view of a completed heel-blank with a rand attached;

Fig. 11 is a view in end elevation of the same; and

Fig. 12 is a perspective view of a separating plate.

Referring now to the drawings, the numeral 1 indicates the base of the machine supported on girders 2, and from which rises the frame indicated generally by the 85 numeral 3. At one side of the frame there is provided a centrally bifurcated bearing 4 in which is mounted a shaft 5, which has secured on one end a band wheel 6. This band wheel is adapted to have a belt (not 90 shown) applied thereto for driving the shaft 5. The said shaft is provided with a crank 7 located in the space between the bearings 4, to which is pivotally connected at its lower end a connecting rod 8, the upper 95 end of which is pivotally connected at 9 to the outer end of an arm 10 which is pivotally mounted toward its inner end, as indicated at 11, in a stirrup 12. The frame 3 provides a vertically-disposed and extended 100 socket 13, which receives and supports a vertical column 14 fixedly secured in said socket in any appropriate way. Formed integral with the under side of the stirrup 12 is a hollow casting 15 which receives and is fixedly secured to the upper end of the column 14. The stirrup 12 is also provided on its upper side with a hollow casting 16 which receives and has fixedly secured therein the lower end portion of a vertical shaft 17. 110 The arm 10 is provided along its lower edge with a blade 18, and has an integral exten-

sion 19 on which is mounted a contact head 20 which is held in adjustable position thereon by a set screw 21. Formed integral with and projecting outwardly from the 5 casting 15 is an arm 22 which is provided along its upper side with a fixed blade 23 with which the blade 18 is designed in operation to coöperate to form a shear or cutter. The numeral 24 indicates a guard extending 10 along and slightly above the upper edge of the blade 23, said guard having a slotted vertical portion 25 by means of which it is adjustably mounted on the arm 22 by a set screw 26. The numeral 27 indicates a yoke 15 which is provided with a cylindrical bearing 28 pivotally mounted on the shaft 17. The outer end of each arm of this yoke is provided with a bearing, 29, 30, respectively, in which is mounted for reciprocal movement a shaft 31 having mounted on its lower 20 end, by means of a set screw 32, a metal socket member 33 carrying a cutting block 34, preferably of wood. Surrounding the shaft 31 is a coil spring 35, one end of which rests against the upper side of the bearing 30, and the upper end of which bears against a collar 36 which is fixedly secured by a set screw 37 to the shaft 31. The pressure of the spring 35 against the collar 36 normally holds the cutting block 34 in its elevated position. The upper bearing 29 has projecting from it a handle 38 by grasping 25 which the yoke 27 may be turned on the shaft 17 as a pivot to the operative or inoperative position. The socket member 33 is formed on its upper side with an integral circular portion 39 which is adapted to receive the impact and pressure of the head 20 when the yoke is turned to bring the cutting block into operative position, as later described.

Mounted on the frame of the machine is a heel-blank holder which comprises two vertically-disposed members, a breast plate 40, and a curved back plate 41. A vertically-disposed member 42 of the frame is provided toward its upper end with a laterally projecting hollow rectangular portion providing side members 43, 44, which extend on 50 either side of the heel-blank holder. The back plate 41 is provided at its upper end with shouldered extensions 45 which rest on the top of the said side members 43, 44. Said back plate is adjustable toward and from the breast plate by means of screws 46 (see Figs. 1 and 2), a lower pair of which pass through the back plate near the sides thereof and have their screw threaded ends engaging in a flange 47 of the vertical frame member 42, from which flange, as will be readily seen by an inspection of Fig. 3, extend the side members 43 and 44 above referred to, while an upper pair of said screws engage the breast plate 40 near the 55 collars 50. Interposed between the heads

of the set screws 46 and the back plate 41 are coil springs 48. By turning the adjusting screws 46 the back plate 41 will be forced by the pressure of the springs toward the breast plate 40, but will be in a position 70 to yield against the resistance of said springs in order to engage firmly and exert pressure upon the lifts and heel-blanks in the holder. The breast plate 40 is supported (see Fig. 8) by means of bolts 49 passing through an upward extension of the flange 47 and having their screw threaded ends engaging in said breast plate, a collar 50, through which the bolts 49 pass, serving to space the breast plate the proper distance from the 75 flange 47. Toward its lower end (Figs. 1 and 2) the breast plate 40 is engaged by contact screws 51 passed through the flange 47, by adjusting which the bottom portion of said contact plate may be sprung inward toward the back plate 41 so as to offer the proper resistance to the movement of the heel-blanks downward as they are built up in the holder. The numeral 52 indicates a die which is removably mounted in the upper 80 end of the heel-blank holder formed by the breast plate 40 and back plate 41, being secured in position by a set screw 53 passing through an upward extension 54 of said breast plate. Surrounding the upper sharpened edge portion of the die 52 is a table 55 which is mounted on a head 56 adjustably secured by a set screw 57 on the upper end of a rod 58. This rod passes through guides 59 and 60, located, respectively, at the top 100 and bottom of the back plate 41, and is yieldably supported by means of a coil spring 61, surrounding its lower portion, the lower end of which spring rests upon the guide 60, and the upper end of which bears 105 against a collar 62 secured on the rod 58. The rear side of the table 55 is provided with a rectangular recess 63 into which extends a block 64, lying flush with the upper surface of the table 55. The ends of this 110 block are shouldered and project beneath the table at opposite sides of its recess, these extending ends being provided with slots 65. Countersunk screws 66 pass through the table and through these slots, and by means 115 of nuts 67 applied to said screws, the block 64 is held in adjusted relation with reference to the rear or breast side of the die 52. Should a larger die at any time be substituted for the one being used, the breast 120 plate 40 will be moved back the appropriate distance by employing a narrower collar 50; and the block 64 will also be adjusted to the proper position to accommodate the larger die. Depending from the block 64 125 are lugs 68 which embrace opposite sides of the extension 54 of the breast plate and guide the table 55 in its movement. As will be seen by an inspection of Figs. 6 and 7, the purpose of the table 55 is to permit the 130

pieces of leather which are to form a pieced lift to be assembled in position over the die. The manner of mounting this table on the rod 58 allows the table to yield under the pressure of the cutting block to permit the leather to be cut by the die as it is pressed down by said cutting block. As soon as the pressure of the cutting block is removed the table, of course, rises to its normal position, in which its upper surface is flush with the cutting edge of the die.

In order to provide for positioning a rand on and applying it to a heel-blank, a rand-holder 69 is provided. This rand-holder is substantially of a horse-shoe shape, its recess having its inner edge undercut to enable it to hold the rand 70, as clearly shown in Fig. 7. The rand-holder is provided with an integral extension 71 which is provided at its outer end with a bearing 72. Extending through this bearing and through an apertured lug 73 of the table 55 is a rod 74. This rod is fixedly secured to the bearing 72, as by a set screw or the like. The lower end 25 of the rod 74 passes through an opening in an arm 75 provided at the lower end of the back plate 41, and has secured to its lower end and projecting from opposite sides thereof stops 76 for engaging opposite sides 30 of the arm 75, whereby to limit the turning movement of the rod 74. This turning movement is for the purpose of bringing the rand-holder 69 into position over the die 52, as shown in Fig. 7, or to turn it to inoperative 35 position, as shown in Fig. 6, and is preferably effected by means of a milled head 77 applied to its upper end. When in position over the die, as shown in Fig. 7, its recessed edge surrounds the die at some distance therefrom, as indicated by the dotted lines, so that when the rand is placed in position under its beveled edge and the cutting block is caused to descend, the said rand-holder will be forced downward around the 40 die, permitting the cutting edge of the latter to engage and cut the rand. The rand-holder, as will be understood, moves downward with the table 55 in the latter operation. The upward movement of the table 55 45 is conveniently arrested by means of a collar 78 secured to the lower end of the rod 74 and adapted to engage the under side of the arm 75. This collar also carries the stops 76 above referred to. In order to indicate to 50 the operator the thickness of each lift cut and forced into the holder, and thereby enable him to determine when each heel-blank has been built up to the proper height, the 55 following indicating mechanism is provided:

Mounted on the upper end of the shaft 17, as by a set screw 79, is a casting 80 provided with a gage 81 at the front of the machine. Projecting from the casting 80 is an integral 60 arm 82 which is apertured to receive the

upper end portion of a rod 83 which reciprocates therein. Mounted on the rod 83 is a pointer 84 which co-operates with the gage 81. Secured to the lower end of the rod 83 is an angle arm 85. Loosely mounted on the 70 shaft 14 and supported on the upper end of the socket member 13 is a sleeve 86 having at one side an integral bearing 87 (see Fig. 1) in which is mounted a shaft 88. Secured to one end of the shaft 88 is a small pulley 75 89. Connected to the periphery of this pulley is one end of a strap 90, the other end of which is secured to the lower end of the angle arm 85 (see Fig. 5). On the opposite end of the shaft 88 there is secured a friction 80 wheel 91. Surrounding the shaft 14 is a torsion spring 92, one end of which is secured at the top of the casting 86 and the other to a collar 93 fixedly secured on the shaft 14 by a set screw 94. The spring 92 85 normally holds the friction-wheel 91 in position to frictionally engage the heel-blanks as they are pressed down in the heel-blank holder, as indicated in Figs. 1, 2 and 8 and by dotted lines in Fig. 3. Thus as each lift 90 is forced into the holder the heel-blanks already in the holder will be forced downward therein a distance corresponding to the thickness of the lift cut, and this movement of the heel-blanks will rotate the friction 95 wheel 91, shaft 88, and pulley 89; and the latter will cause the strap 90 to be wound a short distance about it, thereby lifting the arm 85 and rod 83 and moving the pointer 84 upward over the gage to thereby indicate the thickness of the lift cut and forced into the holder. The operator, of course, knows to what height the heel-blanks are to be built; and by observing the gage and selecting the appropriate thickness of 100 leather, especially for the final lift, he is thereby enabled to make all the heel-blanks of uniform height. When the heel-blank has been completed it is, of course, necessary to restore the pointer 84 to the zero position. To accomplish this there is secured on the side of the sleeve 86 facing the operator an arm 95, by grasping which the operator can easily turn the sleeve 86 to move the wheel 91 from contact with the heel-blank, 110 when the weight of the rod 83 immediately causes it to fall and carry the pointer downward to the bottom of the gage. In this operation, as will be readily understood, the strap 90 will be unwound from the pulley 89 115 due to the fact that by removing the friction wheel from contact with the heel-blank the said wheel, shaft 88, and the pulley 89 are free to turn.

The numeral 96 indicates a scraper, which 125 is mounted on the upper end of a rod 97; this rod passes through an aperture in a flange 98 on the side member 43 and at its lower end through an apertured lug 99 located near the lower end of said side mem- 130

ber. Secured on the rod 97 is a collar 100 (Fig. 5) having a flat side adapted to ride against the face of the side member 43 to keep the rod 97 from turning, and between 5 said collar and the apertured lug 99, and surrounding the rod 97, is a coil spring 101, which thereby supports the rod 97 and scraper 96, the upper edge of which latter is held slightly below the bottom of the cutting block 34. In the depression of the cutting block the scraper is free to be pressed downward against the resistance of the spring 101, and is sufficiently close to the under side of the cutting block at all times 15 to remove from it any pieces of adhering leather, as the cutting block is turned from the operative position shown in Fig. 4 to the inoperative position shown in Fig. 3.

In operation, as the shaft 5 is continuously turned by the band wheel 6, the connecting rod 8 will cause a continuous reciprocation of the arm 10 carrying the blade 18 and of the extension 19 carrying the head 20. The operator selects a piece of leather, 25 and inserting it beneath the guard 24, the blade 18 coöperating with the blade 23 will cut the same on a perfectly straight line. This piece of leather the operator then places upon the table 55 over the die 52, and 30 it may be represented by the piece shown at the left in Fig. 6. A second piece of leather, such as shown by the central piece in Fig. 6, will be provided in a similar way with two straight edges, and adjusted in position next to the first piece, and then a third 35 piece will be provided with a straight edge and adjusted in position next to the second piece, as shown. It will be understood, of course, that the cutting of the piece of 40 leather is not limited to forming such shapes as shown in Fig. 6, as more or less than three pieces can be used, and the straight edges will be provided as may be required to permit the piece being cut to lie closely adjacent to the preceding piece placed on the table 55 over the die. The pieces of leather being assembled in the manner described on top of the die, the operator grasps the handle 38 and turns the cutting block 34 to a 45 position over the die. In this operation an expert can so time the movement as to cause the circular portion 39 to pass under the head 20 while the same is elevated. Should he not do so, however, no harm is done, as 50 the side of the portion 39 will simply strike the side of the head 20 and when the latter next rises the former will immediately slip under the head. As the latter descends, the cutting block is forced downward, pressing 55 the pieces of leather over the die to cut a lift therefrom and simultaneously force it into the die. The cutting block is then again turned to one side, or to the position shown in Fig. 3. A suitable can of paste (not 60 shown) is preferably supported on the ma-

chine in easy reach of the operator who next applies this paste to the lift in the die and proceeds to assemble other pieces of leather upon the die in the same manner as previously described. This operation continues 70 until the heel-blank proper has been built to the desired height, after which the next operation is to apply the rand to the heel-blank. This is done by the operator grasping the knob 77 and turning the rand-holder 69 from the position shown in Fig. 6 to that shown in Fig. 7, and then inserting a rand 70 under said holder; after which the cutting block is again turned to operative position, and the rand is cut and simultaneously forced into the holder and into firm contact with the heel-blank. The latter will then have the appearance shown in Figs. 10 and 11, in which the rand 70 is shown firmly 75 united to the heel-blank proper, indicated by the numeral 102. In order to press the lifts of the heel-blanks firmly together, and to press the rands firmly against the heel-blanks, to insure the firm union of the assembled pieces, and at the same time permit sufficient time to elapse before removing the heel-blanks from the holder to allow the paste applied to the lifts to set, the invention contemplates the building up of a series of separated heel-blanks in the holder, 80 the pressure being afforded by the continuous forcing of the heel-blanks downward in the holder against a desired degree of resistance regulated by adjusting the contact screws 51, as previously described; and the time element being afforded by the gradual forcing of each heel-blank through the holder, as above described. In proceeding thus, separating plates 103 are employed 85 which are preferably provided with beveled edges 104 to conform to the bevel of the rand 70, and after each rand is applied and cut a plate 103 is placed in position on top of the heel-blank, as shown in Fig. 8, and the succeeding heel-blank is built up on top of 90 this plate. This operation continues until ultimately the first heel-blank so constructed 95 will be forced out of the bottom of the holder and will be found to have its pieces firmly united and with the paste set, and in 100 this and other respects to be in condition for the compression, which latter operation, of course, is performed in a separate machine in the ordinary way. It will thus be seen that the invention presents a 105 constantly-acting cutter for enabling the operator to rapidly impart straight edges to the pieces of leather selected, and that the movement of this cutter also affords a means for actuating the cutting block, so that extreme 110 simplicity, facility of operation, and economy of working parts is secured. It will also be noted that not only does the invention provide a ready means for assembling 115 and cutting pieced lifts, but it also affords 120

equal facility for the rapid building of complete heel-blanks with the rand applied thereto, by reason of the fact that the lifts are cut and formed into a heel-blank as part 5 of the same operation, and the rand applied in the same manner; and by continuing this process and separating the heel-blanks in the manner described adequate pressure is applied to the heel-blanks as they are gradually forced downward in the holder to cause the parts thereof to be firmly united and the requisite time is afforded to permit the paste used in cementing the parts together to set.

15 15. It has been found in actual operation that it is not necessary to use nails in heel-blanks thus constructed, as the lifts are so firmly united that they will not become displaced in the subsequent operations to which the 20 heel-blanks are subjected. If preferred, however, one or more nails may be applied to each heel-blank by an ordinary nailing machine, as will be understood by those skilled in the art.

25 25. It will be obvious to those skilled in the art that the present machine can be used for making a continuous log, such as are now employed in the art, and from which individual lifts are cut or sawed off, instead of making separate heel-blanks by interposing plates between successive series of 30 assembled lifts, as described herein.

We claim:

1. In a machine of the class described, in 35 combination with a die, a constantly-reciprocable, pivotally-mounted actuator located above said die, and a swinging cutting-block movable to a position under said actuator.

40 2. In a machine of the class described, in combination with a die, a reciprocating actuator located above said die, a swinging frame, and a cutting-block yieldably mounted in said frame and movable thereby to a position over said die and under said actuator.

45 3. In a machine of the class described, in combination with a die, a pivotally-mounted bar having an extension located above said die, a cutting-block mounted on the 50 machine and movable to a position over said die and under said extension, and means for rocking said bar on its pivot whereby its extension will engage and depress said cutting-block.

55 4. In a machine of the class described, in combination with a die, a pivotally-mounted bar having an extension located above said die, a cutting-block mounted on the machine and movable to a position over 60 said die and under said extension, and means for constantly rocking said bar on its pivot whereby its extension will engage and depress said cutting-block when the latter is moved to a position under said extension.

65 5. In a machine of the class described, in

combination with the combined die and heel-blank holder of indefinite length, an indicator coöperating therewith and adapted to frictionally engage the column of lifts and to be actuated by the movement thereof in 70 said holder to indicate the thickness of successive lifts cut by said die and forced into said holder.

6. In a machine of the class described, in combination with a combined die and heel-blank holder of indefinite length, a cutting-block coöperating with the die, and means coöperating with the holder and adapted to frictionally engage the column of lifts and to be actuated by the movement thereof in 75 80 said holder to indicate the thickness of successive lifts cut by said die and forced thereinto by said cutting-block.

7. In a machine of the class described, in combination with a combined die and heel-blank holder of indefinite length, an indicator having a member adapted to be moved, against the force of gravity, by the movement of a column of lifts in the holder, and means for interrupting at will the operative 85 90 relation of the indicating device with said column to permit said member to fall to the zero position.

8. In a machine of the class described, in combination with a combined die and heel-blank holder of indefinite length, a cutting-block coöperating with the die, an indicating device comprising a friction wheel adapted to engage and be rotated by the column formed by lifts successively cut by 100 said die and forced downward therein by said cutting-block, and a member actuated by the turning of said wheel to indicate the thickness of the successive lifts cut, and means for moving said wheel out of engagement with the column of lifts to permit said member to return to the zero position.

9. In a machine of the class described, in combination with a combined die and heel-blank holder of indefinite length, a cutting-block coöperating therewith, a spring-controlled pivoted support, a rotatable shaft mounted on said support, a friction wheel mounted on one end of said shaft and adapted to engage a movable column of lifts in 110 115 the holder, a pulley mounted on the other end of said shaft, a gage, a reciprocable rod carrying a pointer coöperating with said gage, a strap connected to the periphery of said pulley and to the lower end of said 120 rod, and means for turning said support against the resistance of its spring to remove the friction wheel from contact with said column, the combination operating as described.

10. In a machine of the class described, in combination with a die and a swinging depressible cutting-block coöperating therewith, a relatively stationary scraper coöperating with said cutting-block, and posi- 125 130

- tioned to have the bottom of the cutting-block pass over and in close proximity to its edge in the swinging movement of said cutting-block.
- 5 11. In a machine of the class described, in combination with a die and a swinging depressible cutting-block coöperating therewith, a depressible but relatively stationary scraper located below and in proximity 10 to said cutting-block, and positioned to have the bottom of the latter pass over its edge in the swinging movement of the cutting-block.
12. In a machine of the class described, 15 in combination with a cutting die, a rand-holder coöperating with said die, and adapted to hold a rand in position on the cutting end of said die.
13. In a machine of the class described, in combination with a die, a depressible table surrounding the die, and a rand-holder coöperating with said die and depressible with said table. 20
14. In a machine of the class described, in combination with a die, a depressible table surrounding said die, and a pivotally-mounted rand-holder coöperating with said die and depressible with said table. 25

In testimony whereof, we have hereunto set our hands in presence of two subscribing witnesses.
